UNITED STATES PATENT OFFICE.

FRANCISCO GALLEGOS ESCOBAR, OF ROSARIO DE SANTA FÉ, ARGENTINA.

APPARATUS FOR THE PHOTOGRAPHIC REPRODUCTION ON PAPER BY MEANS OF ELECTRIC LIGHT.

1,320,849.

Specification of Letters Patent.

Patented Nov. 4, 1919.

Application filed September 18, 1918. Serial No. 254,592.

To all whom it may concern:

Be it known that I, FRANCISCO GALLEGOS ESCOBAR, subject of the Kingdom of Spain, residing at No. 852 Corrientes St., Rosario de Santa Fé, Argentina, have invented certain new and useful Improvements in Apparatus for the Photographic Reproduction on Paper by Means of Electric Light, of which the following is a specification.

10 The present invention refers to an apparatus for photographic reproduction on paper by means of electric light and has for object an apparatus which permits of a considerable number of copies being taken rapidly and economically.

The invention has also for object an automatic apparatus which permits of the exact regulation of the time of exposure and the intensity of the light.

20 The invention has also in view other objects which will be specified in the course of the present specification and which will be specially noted in the claims which follow it.

In order that the invention may be clearly understood and easily operated, it has been represented in its preferable form of construction in the drawings attached, in which:—

Figure 1 is a front view of a complete apparatus in accordance with the invention.

Fig. 2 is a vertical cross-section along the line A—B of Fig. 1.

Fig. 3 is a plan view of the same.

Fig. 4 is a vertical cross-section along the line C—D of Fig. 3.

Fig. 5 is a detail, on an increased scale of the cover of the printing-box, in which the closing appliances are illustrated.

Fig. 6 is a similar view, at right angles to the foregoing.

Fig. 7 is a plan view of the cover of the printing-press.

Fig. 8 is a side view of the same.

Fig. 9 is a plan view on an increased scale of the box for the automatic regulation of the light.

Fig. 10 is a vertical section of the same along the line E—F of Fig. 9.

Fig. 11 is a longitudinal section of the said box in which the closing appliances are specially illustrated, and finally,

Fig. 12 is a similar view taken in the opposite direction.

In all the figures mentioned the same reference numbers indicate the same or corresponding parts.

The apparatus in accordance with the present invention is formed by a wooden frame in the form of a pedestal 13, on the top of which is placed the apparatus proper. The latter is formed by a central case 14 intended for the printing-press and provided with a cover 15 in which is fitted a fixed transparent glass 16 and a ground glass 17 capable of sliding in guides 18 in such a manner that it can be removed and inserted at will, in order to regulate the intensity of the light of the lamps 19 which are placed inside the said press. The cover 15 is mounted on hinges and it is held closed by a metal fitting at right angles to and solidly affixed to the lower edge of the cover, as shown at 20, which hooks into the folded end of a spring strip 21 solidly affixed to the side of the box. The cover closes by its own weight and hooks automatically and in order to open it a pin 22 is provided, which has a head 23, which when in a normal position is flush with the outer surface of the press, and which when pressed inward acts on the spring 21, which recedes from and releases the hook. A spring 24 fixed to the body of the case tends to hold it open when the hook is released. The upper portion of the printing press is closed by a cover 25 (Figs. 7 and 8) formed by two sections 26 and 27, joined by hinges and provided with springs 29 which tend to hold one of the sections open. Each of the said sections is provided with handles 30 of any appropriate shape to facilitate handling. At each side of the central press is a box 31 and 32 exactly alike and intended respectively to hold the paper for printing and the paper already printed; these boxes are provided with covers 33 mounted on hinges, which in their normal condition remain closed by their own weight and which may be lifted by means of cords 34 which, passing over pulleys 35, mounted on supports 36, conveniently arranged, are attached to the upper portion of a pedal 37 at the foot of the apparatus.

By pressing the said pedal the two covers 31 and 32 are simultaneously raised for the purpose which will be explained in due

course, and on relaxing the pedal the covers close again by their own weight. If desired there may be fitted, beneath the two boxes referred to, drawers 38 which can be used 5 for various purposes.

At the back of the apparatus, and in the center, is fixed a support 39 to which is fitted a lamp 40 preferably colored yellow, for the purpose which will be in due course specified.

41 is a socket for the electric connection to the lamps of the apparatus. From the said socket runs a wire which carries the fuse 42 and continues by 43 to one of the 15 terminals 43' of the adjustable automatic interrupting apparatus. From the other terminal 44' runs another wire 44 which goes to the lamps 19 and continues along 45 to a plate 46 immersed in an acidulated 20 bath at the bottom of the apparatus, which plate is by preference of an undulating shape in order to give it a greater surface, and which is solidly fixed to the lower end of a lever 48, pivoted at 49, by means of 25 which its position may be regulated with respect to another similar fixed plate 51 adjusted also inside the said bath and joined by a wire 50 with the said socket 41. When the automatic interrupter is closed the circuit is also closed through the lamps 19 and the bath 47, which permits of regulating the intensity of the light of the said lamps 19. 52 is a wire which running from the wire 43, before it enters the interrupting 30 device, goes to a red light 53 which is placed inside the printing press, and which remains constantly alight as will be understood by the arrangement of the circuits as described. 54 are switches fitted 35 on the front of the apparatus, by means of which various combinations can be made in the circuits of the lamps 19.

55 is the box in which are inclosed the parts corresponding to the automatic voluntary regulation of the time allowed for printing, the duration of which naturally depends upon the strength of the plate and the sensitiveness of the paper employed and which should be regulated in each case. 56 is a rail fixed longitudinally to the said box, of some conducting substance, and which carries the terminal 43' to which is connected the wire by which the current enters the apparatus. 57 is another rail 55 parallel to the first and double, which by means of the terminal 44' is connected to the outgoing wire of the interruptor. 58 is a third rail, parallel to the former two and electrically isolated from them. 59 is 60 a carriage capable of sliding along the two rails first mentioned. This carriage has an electric contact 60, electrically connected with the rail 56 and capable of establishing contact with a contact-piece 70 pivoted at 71 65 and connected electrically with the rail 57

in such a manner that when the pieces 69 and 70 are in contact the circuit of the lamps 19 is closed. An angular lever 72, one of the arms of which goes under the contact-piece 70 serves to cut the contact 70 between 70 and 69 when by the sliding motion of the carriage along the said rails the said lever strikes against a lever 78 pivoted at 79 and solidly fixed to a screw-piece 80 which is capable of sliding in a slot 81 fitted at the upper part of the box 55 and the position of which may be regulated at will. The lever 72 is articulated by means of a bar 73 to a horizontal lever 74 pivoted at 75 and capable of moving at an angle determined by the guide 76. The said lever 74 is joined by a spring 77 to a point on the carriage 59 in such a manner that when in a normal position it tends to keep closed the contact between 69 and 70. The carriage 59 carries at one of its extremities an insulated piece of metal 82 to which is hooked the end 83 of a cord 84 which, passing over pulleys 85 ends in a counter-weight 86, placed in the lower part of the apparatus. The object of this counter-weight is to constantly draw the carriage 59 in a certain direction. Solidly affixed to one side of the carriage 59 is a rack 60 which interacts with a pinion 61 fixed on the end of 95 an axle 65, capable of revolving in bearings 63, solidly attached to a box 62. On the said axle is mounted a toothed wheel 64 which couples with another toothed wheel of smaller size 66 mounted upon the same 100 axle as another toothed wheel 67' which in turn couples with another toothed wheel 67, solidly fixed to an axle on which is mounted a fly-wheel 68. This arrangement serves to regulate the traveling speed of 105 the carriage 59 as will be clearly understood.

87 is a second carriage arranged to slide along the rails 57 and 58 and upon which at 88 is pivoted an angular lever one of 110 the arms of which 89 lies, when in a normal position, in the track of the movement of the lever 74 of the carriage 59 previously referred to, while the other arm 90 is held in this position by the action of a spring 115 91. 92 is a cord fixed to one end of the said carriage, and which passing over pulleys 93, ends at a pedal 94, placed at the lower part of the apparatus and which serves to communicate to the said carriage 120 a traveling movement toward the right. The other end of the said carriage carries an insulated piece of metal 95 joined by means of a hook 96 to the end of a cord 97 which passing over pulleys 98 ends in 125 a counter-weight 99 at the lower part of the apparatus, which tends to draw the carriage toward the left. A stop 100 suitably placed in the track of the arm 90 of the said lever controls the movement of the 130

same and its disengagement from the lever 74 of the first mentioned carriage.

In working the machine, the pedal 94 is pressed, which causes the carriage 87 to travel toward the right drawing with it the carriage 59 by the engagement of the lever-arm 89 with the lever 74 until the arm 90 of the former lever strikes the stop 100. During this time, by the open position of the lever 74 the circuit of the lamps 19 is cut. As soon as the disengagement has been brought about by the action of the spring 77 the said circuit is closed and the lamps 19 are lighted and so continue during the return movement of the carriage 59 until the moment when the device 72 strikes the stop 78, at which moment the circuit is cut and the lamps are extinguished. The return movement of the carriage 59 is made by the action of the counter-weight 86. At the same time the carriage 87 also returns to its original position by the action of its counter-weight 99. The position of the regulating stop 78 with respect to the fixed stop 100, regulates therefore, the duration of the exposure. This regulating stop may be moved along the slot 81 by loosening the screw 80 and tightening it suitably in order to keep it in the desired position.

This box is closed by an elbow-shaped lever 101, pivoted at 102 and directed by a guide-piece 103, and which has solidly fixed to it a hook 104 which by means of a spring 105 is held constantly in contact with a hook on the lid, not shown in the drawings. It is evident that by pressing down the lever 101, which in its normal position is on a level with the said lid, the hook is disengaged and the lid is freed, a spring 106 serving to raise it automatically.

The apparatus is operated as follows: The duration of the exposure is adjusted in the manner specified, according to the strength of the plate and the sensitiveness of the paper, the intensity of the light being also regulated and the number of lamps considered suitable, lighted by means of the switches. The pedal 77 is then pressed which results in opening the two boxes 31 and 32, a sheet of paper being extracted from the former and placed in the printing press, upon which is then placed the spring-cover and the pedal is released, the side boxes 31 and 32 thereupon closing by the weight of their lids. The other pedal 94 is then pressed and the carriage 87 runs to the right until on arriving at the stop 100 it frees the carriage 59 which it had drawn along with it, the latter carriage thereupon running back by the action of its counter-weight, regulated by the fly-wheel device specified. During this backward movement the lamps 19 remain alight until the moment when the stop 78 comes into action. The pedal 37 is then pressed again and the boxes

31 and 32 open, the operator passing with the left hand the printed paper to the latter and passing with the right a sheet of sensitized paper from the former to the central press, continuing in this manner until the operation of printing is finished. With an apparatus of this kind it is possible to print, as may be readily understood, a large number of copies in a short space of time.

In certain cases, either as a result of the skill of the operator or the simplicity of the operation, there is no need to regulate automatically and exactly the duration of the exposure and for this purpose the apparatus which is the object of this invention has a special device which permits of disconnecting the carriage 59, the circuits being then established by means of a set of levers which will now be described. Along one of the sides of the box of the interrupter are fixed wooden guides 107 and 108, between which is a metal strip 109 provided with a rim. This metal strip carries two diagonal guides 110 in which is capable of sliding a stop 111 solidly fixed to the wooden guides. A spring 112 tends to hold the said strip in its extreme position toward the left. A lever 113 is connected by means of a joint at its lower end to the opposite end of the said strip 109 in such a manner that by moving the said lever to its left position the strip 109 moves to the right against the pull of the spring 112. This movement to the right results in the movement of the strip 109 outward as a consequence of the arrangement of the diagonal guides 110, thus bringing pressure to bear upon the arm 90 of the lever of the second carriage, against the action of the spring 91, preventing its contact with the lever 74. In this manner, when by the action of the pedal 94 the carriage 87 runs to the right it does not draw with it the carriage 59 which then remains immovable. The lever 113 has its lower end also jointed with the arm 114 of an angular lever pivoted at 115, the other end of which 116 is arranged to establish contact with the end of the rail 56. When the lever 113 is pressed to the left, this contact is established and communicated to the support 117 of the lever, upon which support is also jointed another lever 118 capable of establishing contact with a contact piece 119 solidly fixed to the carriage 87 and connected electrically with the rail 57. 121 and 122 are springs which tend to return the levers to their normal positions. By placing the lever 113 in its left hand position, when the pedal 94 is pressed the carriage 87 runs freely to the right until its contact piece 119 establishes contact with the lever 118, thus closing the circuit. This circuit remains closed as long as the pressure on the pedal 94 is maintained and when the latter is released the carriage runs back by the action of the counter-weight 99, the

lever 118 returning to its normal position and breaking the circuit rapidly, by means of the spring 121.

During the whole time the machine is in operation the external yellow lamp is kept alight in consequence of its circuit being independent of the internal circuit of the apparatus and the interior red light 53 is also kept alight as it is in a circuit which is independent of the automatic interrupter.

It is evident that in the apparatus of the present invention various modifications of construction and of detail may be introduced without thereby departing from the scope of the present invention, which is clearly determined in the clauses of the claim which are appended to this specification.

Having thus specifically described and determined the nature of the present invention and the manner of its operation, I declare that what I claim as being of my invention and exclusive right is:—

1. An apparatus for printing photographic copies by electric light, comprising in combination a supporting frame, a printing press in the center of the frame, a plurality of lamps within the press, electrical circuits for supplying current to the lamps, switches placed in the circuits, an automatic interrupting and regulating device interposed in the circuits of the lamps, and means for regulating the strength of the current including an acidulated bath inserted in the circuits of the lamps, substantially as described and for the purpose specified.

2. An apparatus as claimed in claim 1 wherein a casing is mounted on the frame, rails arranged in the circuits of the lamps carriages slideable on the rails, contact members on the carriages, stop levers for coacting with the contact members, and means for regulating the position of the stop levers.

3. An apparatus as claimed in claim 1, wherein means are provided for throwing out of action the automatic circuit regulator and for simultaneously bringing into action the interrupter.

4. An apparatus for printing photographic copies by electric light, comprising in combination a supporting frame, a printing press mounted in the center of the frame, a plurality of lamps in the press, electrical circuits for supplying current to the lamps, switches interposed in the circuits, a slidably mounted regulator in circuit with the lamps, a slidably mounted interrupter, coöperative levers on the regulator and the interrupter, means for actuating the interrupter to cause

movement thereof in one direction and to cause coaction between the levers on the regulator and the interrupter to insure of the movement of the regulator in the corresponding direction, a stop for coacting with the lever on the interrupter for causing disengagement of the coacting levers, independent means for returning the regulator and the interrupter subsequent to release, coöperative contact members on the regulator, another lever for coacting with the contact members for cutting out the contact between the contact members and an adjustably mounted stop member for coacting with the last mentioned lever on the regulator.

5. An apparatus as claimed in claim 4, wherein a slidably mounted contact strip is provided and normally positioned to allow operation of the lever on the interrupter, manually operative means associated with the contact strip to cause the strip to coact with the lever on the interrupter to prevent coaction of the said lever with the corresponding coöperative lever on the regulator, and secondary circuit closing means engageable by the interrupter when the operation of the latter is controlled by the last mentioned manually operable means.

6. An apparatus as claimed in claim 4, wherein means are provided for throwing out of action the automatic circuit regulator and for simultaneously bringing into action the interrupter.

7. An apparatus as claimed in claim 1, wherein the interrupting and regulating device comprises a casing on the frame, rails interposed in the lamp circuits, regulating and interrupting carriages on the rail, contact members on the regulating carriage arranged in circuit with the rails, one of the contact members being in the form of a lever, coöperative levers on the carriages for coacting with the lever, contact members, a stop lever on the casing for coöperating with the lever contact member, means for adjusting the position of the stop lever, a pedal operatively connected with the interrupting carriage for causing movement of the carriages in one direction, a stationary stop abutted by the lever on the interrupter for causing dislodgment of the coöperative levers to release the regulator carriage weight, actuatable cables connected to the carriages and speed controlling means associated with the regulating carriages.

In testimony whereof I affix my signature.

FRANCISCO GALLEGOS ESCOBAR.
